UNITED STATES PATENT OFFICE

ROBERT E. SCHRODER, OF CHICAGO, ILLINOIS, ASSIGNOR TO GOODMAN MANUFACTURING COMPANY, OF CHICAGO, ILLINOIS, A CORPORATION OF ILLINOIS

DRILLING MECHANISM

Application filed October 19, 1928. Serial No. 313,445.

My invention relates to a new and novel means for drilling holes of a large diameter in coal or other analogous substances and has for its principal object to provide a machine for making breakthroughs in mines having a new and improved drilling or cutting means with a cuttings expulsion means incorporated therewith. Other objects of my invention will appear from time to time in the following specification.

Heretofore breakthroughs have been driven by hand to permit ventilation of the working places in the mine. This is an expensive operation requiring a good deal of hand labor, and requiring the use of an undercutting mining machine to make the cutting operation, and furthermore cutting away more coal than is required for adequate ventilation.

The device embodied in my invention will quickly and efficiently cut breakthroughs at a minimum cost and remove enough material to provide ample ventilation for the working face and provide an opening of large enough diameter to receive a man and to allow said man to escape through said breakthrough in cases of necessity, as an explosion or cave in.

My invention may best be understood by reference to the accompanying drawings, wherein;

Figure 1 is a top plan view of the device embodied in my invention;

Figure 2 is a side elevation of the device shown in Figure 1 with parts broken away and in section to more clearly show the details of my invention;

Figure 3 is a fragmentary front end view of the device shown in Figure 1 with the drilling element in a different position than is shown in Figure 1, with parts in section to more clearly show the details of construction thereof;

Figure 4 is a fragmentary sectional view showing a means for raising and lowering the drilling means embodying my invention;

Figure 5 is an enlarged fragmentary sectional view showing the details of construction of the drilling mechanism embodying my invention;

Figure 6 is a sectional view of the cuttings

propelling mechanism taken on line 6—6 of Figure 5;

Figure 7 is a fragmentary enlarged end view of the device shown in Figure 1 showing the details of the gearing mechanism for 55 rotating and feeding the drilling mechanism;

Figure 8 is an enlarged fragmentary top view of the device shown in Figure 1 with parts shown in section to more clearly show the details of the gearing mechanism for 60 rotating and feeding the drilling mechanism;

Figure 9 is an enlarged fragmentary sectional view taken on line 9—9 of Figure 2;

Figure 10 is an enlarged fragmentary sectional view taken on line 10—10 of Figure 2; 65

Figure 11 is a fragmentary sectional view showing an extension to the drilling arm;

Figure 12 is an end elevation of the drilling mechanism embodied in my invention driving a breakthrough in a mine wall; 70

Figure 13 is an end elevation of the drilling mechanism embodied in my invention driving a breakthrough in a mine wall with the extension shown in Figure 11 added thereto;

Figure 14 is an end elevation of the drilling mechanism embodied in my invention driving a breakthrough in a mine wall with the drilling mechanism further advanced in said mine wall than is shown in Figures 80 12 and 13; and

Figure 15 is a sectional view taken on line 12—12 of Figure 5.

Like numerals refer to like parts throughout the various figures.

Referring now to the drawings, I have shown a drilling mechanism generally indicated at 1 supported on a portable power truck 2 which comprises a truck frame 3 supported on axles 4 and track wheels 5, 5. Suitable power means are provided on said truck to drive the drilling mechanism and to drive said truck from working place to working place which may be of any form, but which is herein indicated as an electric motor 6.

The drilling mechanism 1 is supported and journaled on a supporting frame 7 freely mounted for either rotatable or vertical move-

ment on a cylinder 8 held in the truck frame 3 by a support 9. Said drilling mechanism is moved about the cylinder 8 by hand and is vertically adjustable thereon by means of a manually operable self-locking screw mechanism. Said screw mechanism herein comprises a shaft 10 threaded in the lower end of the supporting frame 7 having a head 11 at its lower end abutting the underside of a flange 12 of a sleeve 13 mounted on the cylinder 8 beneath the supporting frame 7 for rotatable movement thereabout, and having a bevel pinion 15 feathered to its upper end driven by a bevel pinion 16 on a shaft 17 which may be driven by a hand crank (not shown) detachably connected with a squared end 19 of the shaft 17. A collar 14 is threaded to the lower portion of the sleeve 13 to prevent vertical movement thereof. It may thus be seen that rotation of the threaded shaft 10 causes vertical movement of the supporting frame 7 to adjust the drilling mechanism 1 for drilling at various heights in the mine wall.

25 The drilling mechanism 1 comprises in general a drilling arm 20 carrying suitable drilling and cutting mechanism at its forward end which will hereinafter be more fully described. Said drilling arm is connected to a movable carriage 21 at its rearward end and is movable with said carriage, and is journaled for translational and rotational movement in a portion 22 of the supporting frame 7 near its forward end. An auxiliary movable support 23 is detachably connectible with the forward portion of the drilling arm 20 to support said drilling arm as it is being fed into the material to be drilled. A plurality of rotatable cutting elements 25 project outward from the drilling arm 20 and are inclined towards the rearward portion of said drilling arm so that the cutting elements adjacent the central portion of said drilling arm engage the material to be cut ahead of the cutters more distant from the center of said drilling arm. Said cutting elements are also rotatable about their axis of inclination at a speed greater than the speed of rotation of the drilling arm 20. A pilot drill 26 is provided on the extreme forward portion of the drilling arm 20 and is rotated by means of a shaft 27 journaled within said drilling arm at a speed higher than the speed of rotation of the drilling arm 20 and in a direction of rotation opposite to that of the drilling arm 20.

30 The carriage 21 is slidably mounted on supporting and guiding bars 28 and 29 interposed between a portion 30 and the portion 22 of the supporting frame 7, and drive shafts 31 and 32 journaled in the portions 30 and 22 of the supporting frame 7 so that movement of the carriage 21 will cause movement of the drilling arm 20 to provide a means for feeding said drilling arm into the

material to be drilled. A threaded shaft 33 is threaded through a portion 34 of the carriage 21 and is journaled in the portions 30 and 22 of the supporting frame 7 so that rotation of said shaft in one direction or the other causes movement of the carriage 21 along the supporting and guiding bars 28 and 29. Said threaded shaft is driven from the motor 6 by a suitable train of reduction gears which will hereinafter more fully be described.

35 The drilling arm 20 is made up of a rearward section 40 and a forward section 41. Said sections are detachably connectible with each other so that an intermediate section 42 having a means to clear the cuttings from the hole being drilled generally indicated at 43 thereon may be interposed between the sections 40 and 41 or so that an extension section 45 may be inserted in said drilling arm 85 to increase the length of said arm when desired. The drilling arm 20 is rotated by a gear 46 keyed to a rearward portion 47 of the rearward section 40 of the drilling arm 20. The rearward portion 47 of the section 90 40 is journaled within the carriage 21 and drives the section 40 of the drilling arm 20 from the motor 6 in a clockwise direction with reference to the face of the coal through a suitable gear train which will hereinafter be 95 described.

40 The drive shaft 27 is journaled within the section 40 of the drilling arm 20. A gear 49 is keyed to the rearward end of said shaft and is connected with the motor 6 through a 100 suitable system of reduction gearing for driving said shaft in a counter clockwise direction or in a direction opposite to the direction of rotation of the drilling arm 20 while a squared socket 50 is provided on the forward end of said shaft. The squared socket 50 is adaptable to receive the squared end of a shaft 53 journaled within the section 41 may be inserted in the socket 50 to drive the pilot drill 26 when the length of the drilling arm 20 is extended beyond the normal length. As herein shown the squared end of a shaft 53 journaled within the section 41 110 may be inserted in the socket 50 to drive the pilot drill 26 or a shaft 54 journaled within the section 42 carrying the cuttings expulsion means 43 may be interposed between the shafts 27 and 53 to provide a means for expelling the cuttings from the drill hole and driving the pilot drill 26 at the same time, or still further a shaft 57 journaled within 115 the extension section 45 may be interposed between the shafts 27 and 54 or 27 and 53 so that the pilot drill 26 may be rotated at various lengths of the drilling arm 20. It may be understood with reference to the drawings 120 that the shafts 53, 54 and 57, have a squared end on one end and a squared socket on the opposite end so that one shaft may always drive the next adjacent shaft.

125 The pilot drill 26 may be of any well known 130

type, but is herein shown as a fish tail type drill detachably connected to the end of a shaft 60 by means of a suitable nut and bolt as indicated at 61. The shaft 60 is journaled within an end piece 62 held on the end of the section 41 of the drilling arm 20 by any suitable means such as nuts and bolts (not herein shown). Said shaft has a groove 63 therein adaptable to receive the end of a set screw 64 to prevent longitudinal movement of said shaft in the end piece 62. A squared end 65 is provided on the shaft 60 to fit in a squared socket on the forward end of the shaft 53 to provide a means for driving said shaft from the shaft 53.

A bevel pinion 66 is provided on the shaft 53 which meshes with and drives a bevel pinion 67 keyed on a shaft 68 and journaled within a portion 69 of the section 41 of the drilling arm 20. The shaft 68 has a cutter holding member 70 keyed thereon which is journaled on the portion 69 of the section 41 of the drilling arm 20. The cutter holding member 70 has a plurality of cutters 72, 72, 72 thereon which may be detachably held thereto by any suitable means, said means being herein shown as nuts and bolts 73. The cutters 72 extend the entire length of the cutter holding member 70 and have a plurality of V shaped teeth thereon. Said cutters are inclined towards the direction of rotation of the cutter holding element 70 and are so arranged that the teeth of each respective cutter are in staggered relation with respect to each other to prevent goring of the material being cut.

It may now be seen that the drilling arm 20 is rotated at one speed in one direction by means of the gear 46 which in turn rotates the cutters 72 about a horizontal axis. It may also be seen that said cutters are simultaneously rotated about the axis of the shafts 68 through the bevel pinions 66 and 67 and the shaft 53 at a higher speed than the speed of rotation of the drilling arm 20 and in a clockwise direction or in the same relative direction as the direction of rotation of the drilling arm 20 so that the cutters 72 will cut in to the material to be cut and not roll along the face of said material as would result if said cutters were rotating in the opposite direction, and that the pilot drill 26 is also rotated by means of the gear 49 and shaft 27 at a higher speed than the speed of rotation of said drilling arm in an opposite direction to the direction of rotation of said drilling arm. This provides a drilling apparatus having a pilot drill rotating at a relatively high speed and cutters inclined rearwardly from the pilot drill 26 and rotating about the axis of said pilot drill at a speed slower than the speed of rotation of said pilot drill to allow for the difference in circumferential speed between the outermost teeth of the cutters 72 and the pilot

drill 26 and also rotating about their axis of inclination so that each cutter may independently perform its cutting operation as said cutters are rotated about a horizontal axis by means of the drilling arm 20 and propel the cuttings away from the next following cutter.

The cuttings expulsion means 43 on the section 42 of the drilling arm 20 comprises a plurality of propellers 75 rotating with the drilling arm 20 and also rotating about an axis perpendicular to the axis of rotation of the drilling arm 20 to clear the drill hole from all cuttings expelled by the cutters 72, 72. One propeller 75 is mounted on one side of the section 42 of the drilling arm 20 and to one side of the shaft 54 journaled in said section while another propeller 75 is mounted on the opposite side of said section and on the opposite side of the shaft 54. The propellers 75 are keyed on the ends of shafts 76 journaled in the section 42 of the drilling arm 20. Worm gears 77 are keyed to each of said shafts and are housed within the section 42 of the drilling arm 20 and are rotated by a worm 78 keyed to the shaft 54 (see Figures 5 and 6) providing a means for propelling the cuttings from the drill hole to prevent said cuttings from clogging the cutters 72 while said cutters are drilling said hole.

Referring now to the means for driving and feeding the drilling mechanism 1, the motor 6 is provided with a skew bevel pinion 80 which drives a skew bevel gear 81 rotatable on the support 9 for the cylinder 8. A hub 82 is provided on the skew bevel gear 80 and has a spur gear 83 integral therewith which drives a spur pinion 84 on a vertical shaft 85. The vertical shaft 85 has a bevel pinion 86 feathered thereon so said bevel pinion may be driven by said shaft at the various elevations of the drilling mechanism 1.

The bevel pinion 86 meshes with a bevel pinion 87 on one end of a horizontal shaft 88 to drive said shaft. The horizontal shaft 88 is journaled on the supporting frame 7 and has a spur gear 89 keyed to its opposite end which drives a spur gear 90 keyed on the drive shaft 31. The spur gear 90 drives a spur gear 91 on the drive shaft 32 and rotates said drive shaft. A spur gear 92 is keyed on the drive shaft 32 and meshes with and drives a spur gear 93 freely mounted on the threaded shaft 33. Clutch jaws 94 are provided on the face of the spur gear 93 and may be engaged by clutch jaws 95 on a clutch member 96 feathered to the threaded shaft 33 so that the spur gear 93 may rotate said threaded shaft in one direction to move the movable carriage 21 rearwardly along the supporting and guiding bars 28 and 29 to withdraw the drilling arm 20 from the completed drill hole at a relatively high rate of speed. A spur pinion 97 is keyed on the outer end of the shaft 32 and meshes with and

drives a spur gear 98 freely mounted on the threaded shaft 33. Friction clutch means generally indicated at 99 are herein provided to rotate the threaded shaft 33 through the 5 spur gear 98 at a lower frictionally controlled speed and in an opposite direction than is obtained from the spur gear 93 thus providing a means to move the carriage 21 forwardly on the supporting and guiding 10 bars 28 and 29 to feed the drilling arm 20 into the material to be drilled. Said friction clutch means may be of any suitable type but is herein shown as a cone clutch of an ordinary construction having one face 100 integral 15 with the spur gear 98 and another face 101 engageable with the face 100 integral with the clutch member 96 so that the threaded shaft 33 may be driven by either the gear 93 or 97 through the same clutch operating 20 means, and so that it is only possible to connect the gear 98 to the threaded shaft 33 when the gear 93 is disconnected from said shaft and vice-versa.

25 The clutch member 96 is operated by a hand wheel 102, through a suitable system of levers of the usual type.

30 The shaft 31 has a keyway 103 extending between the portions 22 and 30 of the supporting frame 7. A spur pinion 104 is feathered on the shaft 31 and has a hub 105 thereon journaled within a portion of the movable carriage 21. A collar 106 is provided on the opposite end of the hub 105 from the spur pinion 104 to abut the portion 35 of the movable carriage 21 so that the pinion 104 may be movable with the movable carriage 21. Said spur pinion meshes with and drives the gear 46 keyed to the rearward portion 47 of the rearward section 40 of the drilling 40 arm 20 to drive said drilling arm. Similarly the shaft 32 has a keyway 107 extending between the portions 22 and 30 of the supporting frame 7 and has a spur pinion 108 feathered thereon. The spur pinion 108 has a hub 45 109 thereon which is journaled within a portion of the movable carriage 21 and has a collar 110 abutting said movable carriage so said spur pinion may move with the movable carriage 21. The pinion 108 meshes with and 50 drives the spur gear 49 keyed to the drive shaft 27 to drive said drive shaft and the pilot drill 26 at a higher speed and in an opposite direction to the direction of rotation of the drilling arm 20.

55 The truck 2 may be driven by any suitable means to move the drilling mechanism about the mine.

As herein shown said truck is driven by a bevel armature pinion 115 on the rearward 60 end of the armature shaft 79 of the motor 6 which meshes with bevel gears 116 and 117 freely mounted on a transverse shaft 118. Friction clutch means 119 and 120 are provided to connect either of the beveled gears 65 116 or 117 with the shaft 118 so said shaft

may be driven in opposite directions by either one of said bevel gears. Drive chains 121 are provided to operatively connect the shaft 118 with the track wheels 5, 5, to drive said track wheels and thus drive the truck 2 in either a forward or rearward direction.

The auxiliary movable support 23 comprises a journal box 123 having a removable cap piece 124 held thereto by means of cap screws or any other suitable holding means. 75 The drilling arm 20 is adaptable to be journaled in said journal box when said drilling arm is in a drilling position transverse of the truck frame 3 and has a collar 125 held thereon by means of set screws 126 so it may bear against the rearward end of the journal box 123 to move said journal box along with said drilling arm as said drilling arm is being fed into the material to be cut. The journal box 123 is supported on guide rails 127, 80 127, extending transversely of the truck frame 3 near the forward end thereof which are slidable in guides 128 in the truck frame 3, by means of upright rods 129 fixed in the journal box 123 and held in a frame member 130 fixed to the guide rails 127. It may here be observed that when the drilling arm 20 is in a drilling position transversely of the truck frame 3 as indicated in dotted lines 85 in Figure 1 that the journal box 123 may be fastened to said drilling arm ahead of the collar 125 and that when said journal box is fastened to said arm, a movable support is provided for said arm which supports said arm as it moves into the material to be cut 90 and thus assures a steady support for said drilling arm when said arm is drilling at a substantial distance beyond the truck frame 3.

95 Figure 1 shows the drilling mechanism 1 extending longitudinally of the truck 2 in a travelling position. The truck 2 travels into the mine room on the mine rails. The truck is stopped where it is desired to drive a breakthrough and the drilling mechanism 1 is turned in the position shown in dotted lines 100 in Figure 1. The auxiliary supporting frame 23 is then fixed to said drilling arm and the drilling mechanism is fed to the face of the coal by means of the threaded shaft 33 and movable carriage 21, the auxiliary supporting frame 23 moving therewith. The pilot drill 26 and cutters 72 are then fed into the coal face and the breakthrough is started 105 as shown in Figure 12. In Figure 12 the mine track is at such a distance from the mine wall that the entire breakthrough cannot be drilled in one operation. When the drilling arm 20 reaches the end of its forward travel the drilling mechanism is stopped 110 and the auxiliary movable supporting frame 23 is disconnected from the drilling arm and the section 40 is disconnected from the section 42. The section 40 is moved rearwardly 115 120 125 130 135

by means of the carriage 21 and threaded shaft 33, and the extension section 45 is inserted between the sections 40 and 42 thereby lengthening the drilling arm 20 to enable 5 said drilling arm to feed its cutting elements further into the coal as shown in Figure 12. The auxiliary support is attached to the extension 42 and the cutting of the breakthrough is continued as shown in Figure 14. In cases 10 where the mine rails are close to the face of the coal it is not necessary to use the extension section 42, said section only being used when the breakthrough is exceptionally deep or where the mine rails are a substantial 15 distance from the face of the coal.

From the description above it may be seen that I have provided a drilling mechanism mounted on a truck adaptable to drill holes of a large diameter such as breakthroughs in 20 a coal mine, which is adjustable to drill at various heights with respect to the truck frame and has an extensible drilling arm adaptable to drill holes of varying depths, and has a movable support to support said 25 drilling arm adjacent the face of the coal beyond the drilling truck. It may also be seen that I have provided a cutting element having a multiplicity of cutters thereon having a pilot drill of small diameter rotating 30 in one direction and a plurality of rotating cutters cutting into the coal and inclined rearwardly from said pilot drill and also rotating about the axis of said pilot drill in an opposite direction to the direction of rotation of 35 said pilot drill and at a slower speed than the speed of rotation of said pilot drill to compensate for the difference in circumferential speed between the pilot drill 26 and the outermost extremities of the cutters 72 and that 40 I have further provided a means of a new and improved design to clear the cuttings from my cutting element.

While I have shown one form of my invention in this specification it will be understood 45 that this form may be varied without departing from the scope of my invention except as limited in the appended claims.

I claim as my invention:

1. In a drilling apparatus, a support, a rotatable drilling arm, a pilot drill journaled within said drilling arm, a plurality of cutters extending radially outwardly from said drilling arm, and a cuttings clearing device on said drilling arm comprising a plurality 50 of propellers rotatable with said drilling arm and rotatable on axes perpendicular to the axis of rotation of said drilling arm.

2. In a drilling apparatus, a support, a motor, a horizontally extending rotatable drilling arm, a shaft journaled within said drilling arm, a pilot drill operatively connectible with the forward end of said shaft, a plurality of cutters extending radially outward from said drilling arm, a cuttings clearing 60 device on said drilling arm rearwardly of said

cutters comprising a plurality of propellers rotatable with said drilling arm, and on axes perpendicular to the axis of rotation of said drilling arm, and driving means connectible with said shaft for rotating said propellers. 70

3. In a drilling apparatus, a support, a motor, a rotatable drilling arm, a shaft journaled within said drilling arm and rotatable in a direction opposite to the direction of rotation of said drilling arm having a pilot drill connectible with the forward end thereof, a plurality of cutters extending radially outward from said drilling arm, a cuttings clearing device on said drilling arm rearwardly of said cutters comprising a plurality of propellers rotatable with said drilling arm and rotatable on axes perpendicular to the axis of rotation of said drilling arm, and gear reduction means connectible with said shaft for rotating each of said propellers about an axis perpendicular to the axis of rotation of said drilling arm. 75

4. In a drilling apparatus, a support, a motor, a rotatable drilling arm, a shaft journaled within said drilling arm and rotatable in a direction opposite to the direction of rotation of said drilling arm, a pilot drill connectible with the forward end of said shaft, a plurality of cutters journaled on radial extensions from said drilling arm, a cuttings clearing device on said drilling arm rearwardly of said cutters comprising a plurality of propellers rotatable with said drilling arm and rotatable on axes perpendicular to the axis of rotation of said drilling arm, a bevel geared connection on said shaft for rotating each of said cutters about its respective radial axis as said drilling arm is being rotated about a horizontal axis, and a worm on said shaft connectible with a plurality of worm gears for rotating each of said propellers. 90

5. In a drilling apparatus, a support, a motor, a drilling arm, a pilot drill journaled within said drilling arm, a plurality of cutters extending radially from said drilling arm and inclined rearwardly with respect thereto and means connectible with said motor for simultaneously rotating said drilling arm in one direction, rotating said pilot drill in an opposite direction and rotating each of said cutters about its respective radial axis as said cutters rotate about the axis of rotation of said drilling arm. 100

6. In a drilling apparatus, a support, a motor, a drilling arm, a pilot drill journaled within said drilling arm, a plurality of cutters extending radially from said drilling arm, means connectible with said motor for translationally moving said drilling arm to feed said drilling arm into the material to be cut, and means connectible with said motor for simultaneously rotating said drilling arm in one direction, rotating said pilot drill in an opposite direction, and rotating each 110 115 120 125 130

of said cutters about its respective radial axis as said cutters rotate about the axis of rotation of said drilling arm.

7. In a drilling apparatus, a support, a motor, a drilling arm, a pilot drill journaled within said drilling arm, a plurality of cutters extending radially from said drilling arm and inclined rearwardly with respect thereto, means connectible with said motor for translationally moving said drilling arm to feed said drilling arm into the material to be cut, and means connectible with said motor for simultaneously rotating said drilling arm in one direction, rotating said pilot drill in an opposite direction, and rotating each of said cutters about its respective radial axis as said cutters rotate about the axis of rotation of said drilling arm.

8. In a drilling apparatus, a support, a motor, a drilling arm, a pilot drill journaled within said drilling arm, a plurality of supports projecting radially from said drilling arm, cutters journaled on said supports, and means connectible with said motor for simultaneously driving said pilot drill in one direction, said drilling arm in an opposite direction, and said cutters about their respective axis in the same relative direction of rotation as said drilling arm.

9. In a drilling apparatus, a support, a motor, a rotatable drilling arm, a pilot drill journaled within said drilling arm, a plurality of supports extending radially from said drilling arm and inclined rearwardly with respect thereto, a plurality of cutters journaled on said supports and projecting radially outward therefrom, means connectible with said motor for rotating said drilling arm in one direction, and means independent of said drilling arm connectible with said motor for rotating the said cutters about said supports, as said supports and cutters are rotated by said drilling arm.

10. In a drilling apparatus, a support, a motor, a drilling arm, a pilot drill journaled within said drilling arm, a drive shaft connectible with said motor and parallel with said drilling arm, means driven from said shaft for rotating said drilling arm, means driven from said shaft for rotating said pilot drill in a direction opposite to the direction of rotation of said drilling arm, a plurality of supports extending radially from said drilling arm and inclined rearwardly with respect thereto, a plurality of cutters journaled on said supports and projecting radially therefrom, and means connectible with said drive shaft for rotating said cutters on said supports simultaneously with rotation of said drilling arm and pilot drill.

11. In a drilling apparatus, a support, a motor, drilling mechanism, including a pilot drill, means for driving said pilot drill from said motor, and a cuttings clearing device rearwardly of said pilot drill comprising a

propeller driven by said means for driving said pilot drill about an axis disposed transversely of the axis of rotation of said pilot drill.

12. In a drilling apparatus, a support, a motor, drilling mechanism including a drilling arm and a pilot drill journaled within said drilling arm, means for driving said drilling arm from said motor, means for driving said pilot drill from said motor, and a cuttings clearing device on said drilling arm and rotatable therewith and driven by said means for driving said pilot drill.

Signed at Chicago, in the county of Cook and State of Illinois, this 16th day of October, A. D. 1928.

ROBERT E. SCHRODER.
